CLAIM

The ornamental design for a smart clock, as shown and described.

DESCRIPTION

FIG. 1 is a top front perspective view of a smart clock, showing our new design.

FIG. 2 is a front elevation view of the smart clock shown in FIG. 1.

FIG. 3 is a rear elevation view of the smart clock shown in FIG. 1.

FIG. 4 is a left elevation view of the smart clock shown in FIG. 1.

FIG. 5 is a right elevation view of the smart clock shown in FIG. 1.

FIG. 6 is a top plan view of the smart clock shown in FIG. 1; and,

FIG. 7 is a bottom plan view of the smart clock shown in FIG. 1.

The broken lines shown in the drawings illustrate the portions of the article that form no part of the claimed design.

1 Claim, 7 Drawing Sheets
